UNITED STATES PATENT OFFICE.

WILLEM C. KORTHALS-ALTES, OF SCHENECTADY, NEW YORK, ASSIGNOR TO GENERAL ELECTRIC COMPANY, A CORPORATION OF NEW YORK.

ALTERNATING-CURRENT MOTOR.

1,219,952.

Specification of Letters Patent. Patented Mar. 20, 1917.

Application filed April 11, 1916. Serial No. 90,460.

To all whom it may concern:

Be it known that I, WILLEM C. KORTHALS-ALTES, a subject of the Queen of the Netherlands, residing at Schenectady, county of 5 Schenectady, State of New York, have invented certain new and useful Improvements in Alternating-Current Motors, of which the following is a specification.

My invention relates to alternating current commutator motors, and particularly to 10 polyphase alternating current commutator motors of the brush shifting type, and has for its object to provide an improved polyphase alternating current commutator motor of the brush shifting type having compound excitation.

The particular object of my present invention is to provide a polyphase alternating current commutator motor adapted to normally 15 operate with series characteristics but at the same time provided with means for giving the motor a relatively low no-load or light-load speed. It sometimes is necessary in certain classes of equipments, such as for example as printing-press machines, 20 calanders, and the like, to operate the apparatus at a relatively low speed under relatively light or varying load conditions. Take, for example, the case of a printing 25 press where a very low speed is necessary for feeding in the paper or for adjusting the rolls. Heretofore, high speed printing press equipments have often been provided with two motors, one of which is employed for 30 the normal high speed operation of the apparatus, while the other, a relatively low speed motor, is employed for feeding the paper, etc. In equipments of this character the apparatus is operated at a very low speed 35 40 while the paper is being fed in and is then run at as high a speed as practicable. Whenever the paper breaks, as frequently occurs in practice, the high speed operation must cease, and the paper must again be fed in with the apparatus running at a very low speed. In two-motor equipments a clutch is 45 provided for at will connecting the low speed motor to the apparatus, but at the same time the high speed motor must be 50 electrically disconnected from the source of electric energy supply, or mechanically disconnected from the printing press apparatus. This necessitates a very complicated control equipment besides an expensive initial outfit. In accordance with my present

invention a single polyphase alternating current commutator motor may be employed for satisfactorily running a printing press at the low speed for feeding in the paper, etc., and for running the printing press at 60 its high normal operating speed.

The low speed required in printing press equipments, and the like, might be obtained by a series motor, if it were not for the fact that such equipments, as a general rule, have 65 very high static friction requiring high torque for starting with a decreasing torque as the apparatus speeds up. A series motor would give the required high torque for starting, but as the load or required torque 70 decreased the speed would increase, and thus, due to the relatively light load after the apparatus has been started, a series motor would speed up rapidly, thereby endangering the operators who are manually feeding the paper through the rolls. The improved motor of my present invention is in effect a series motor having a definite limited low no-load or light-load speed, so that 75 the motor can be operated under the conditions specifically mentioned hereinbefore 80 without the danger of having the speed increase with variations in load.

The improved motor of my present invention and its operating characteristics will be 85 more readily understood by reference to the figure of the accompanying drawing in which the windings of the motor and their electrical connections and relations are diagrammatically illustrated. The motor has 90 a polyphase stator or field winding 5 adapted to be directly connected to a polyphase source of alternating current energy 6 by means of a suitable switch 7. The motor diagrammatically represented in the drawing 95 is a three-phase motor, and the stator winding 5 is wound like the primary winding of an ordinary three-phase induction motor. In the accompanying drawing the phases of the stator winding are represented 100 as star-connected, the circle 8 representing the neutral point of the winding, but it will be obvious to those skilled in the art that the stator winding may be either star or delta connected.

The rotor or armature winding of the motor is a commutated winding similar to the armature winding of an ordinary direct current motor. This rotor winding and its co-operating commutator are diagrammati- 110

cally represented in the drawing by the circle 9. A set of stationary brushes 11, 12, and 13, and a set of movable brushes 14, 15 and 16 bear on the commutator of the rotor 5 winding. The three brushes in each set have a polyphase arrangement, that is to say, the three brushes of each set are positioned on the commutator 120 electrical degrees apart. The movable brushes 14, 15 and 16 are preferably carried by a single brush-holder yoke 17, which may be manually moved by a handle 18 for shifting the brushes 14, 15 and 16 with respect to the brushes 11, 12 and 13, respectively.

15 The stationary and movable commutator brushes are connected in pairs to the terminals of the secondary winding 21 of a series transformer whose primary winding 20 is connected in series with the stator winding 20. Thus, one phase of the secondary winding of the series transformer is connected between brushes 11 and 14, the second phase is connected between brushes 12 and 15, while the third phase is connected between 25 brushes 13 and 16. Movement of the brush yoke 17 thus varies the amounts of the armature winding across which the phases of the secondary winding of the series transformer are connected, and thus varies the 30 degree of series excitation of the motor.

A polyphase autotransformer 22 is connected across the main polyphase conductors connecting the motor to the source 6. The autotransformer 22 is thus in effect a shunt 35 transformed and its windings are star-connected as indicated in the drawing. The stationary brushes 11, 12 and 13 are connected by conductors 23, 24 and 25, respectively, to suitable taps on the autotransformer. A 40 switch 26 is included in the conductors 23, 24 and 25.

The connection of the stationary brushes 11, 12 and 13 to the autotransformer 22 causes a current to flow in the rotor winding 9 which produces a shunt excitation of the motor. If the switch 26 is closed, and the coöperating pairs of stationary and movable brushes occupy the same positions on the commutator, that is, if brush 14 is co-50 incident in position with brush 11, etc., the motor will operate as a plain shunt motor. The speed of the motor will depend on the transformation ratio of the autotransformer 22. By shifting the brushes 14, 15 55 and 16 away from coincidence with brushes 11, 12 and 13, respectively, a current derived from the series transformer 20-21 will flow through the rotor winding, thereby producing a series excitation. The torque 60 of the motor will now have both shunt and series characteristics, or in other words, the motor will operate with compound characteristics. Under such conditions it will be impossible for the motor to run faster 65 than the shunt speed, since the shunt con-

nexion will cause the motor to operate as a generator and so prevent the speed of the motor rising. The shunt connection can hence be used for dynamic braking, since the shunt excitation will produce a shunt 70 generator action in the machine if the speed rises slightly above the normal shunt speed. It will also be evident that the shunt excitation which the motor receives from the autotransformer 22 operates to limit the no-load speed of the motor. It will be obvious 75 that the autotransformer 22 may be an ordinary transformer with independent primary and secondary windings and in either case may be star or delta connected, and further that the series transformer 20-21 may, if desired, be an autotransformer and 80 may also be star or delta connected.

As hereinbefore suggested the improved 85 motor of my present invention is particularly adapted for use in equipments operating normally at relatively high speed, but in which a relatively low no-load or light-load speed is frequently required. When applied to such equipments the switch 26 90 will be closed when the relatively low speed is desired, as, for example, when feeding in paper in a printing-press machine. Upon the completion of the operation requiring the relatively low speed, the switch 26 may 95 be opened and the motor will then operate with series characteristics. Speed variations can be obtained by shifting the movable brushes 14, 15 and 16, and in practice 100 these brushes will be shifted to obtain the desired speed of operation. It will of course be understood that any suitable control apparatus may be provided in combination with my improved motor to facilitate the ordinary electrical changes in the motor 105 connections for the particular equipment in hand.

What I claim as new and desire to secure by Letters Patent of the United States, is:—

1. A polyphase alternating current commutator motor having a polyphase stator winding and a commutated rotor winding, a polyphase arrangement of movable brushes and a polyphase arrangement of stationary brushes bearing on the commutator of said 110 rotor winding, a polyphase series transformer included in the circuit of said stator winding, said movable and stationary brushes being connected to said series transformer so that varying degrees of series excitation can be produced in said rotor winding by movement of said movable brushes, and a polyphase shunt transformer adapted 115 to be connected to certain of said brushes. 120

2. A polyphase alternating current commutator motor having a polyphase stator winding and a commutated rotor winding, a polyphase arrangement of movable brushes and a polyphase arrangement of stationary 125 brushes bearing on the commutator of said 130

rotor winding, a polyphase series transformer having its primary circuit included in the circuit of said stator winding and its secondary circuit connected between said stationary brushes and said movable brushes so that varying degrees of series excitation can be produced in said rotor winding by moving said movable brushes, and a polyphase shunt transformer having its primary circuit connected in shunt relation to said stator winding and its secondary circuit connected to said stationary brushes.

3. A polyphase alternating current commutator motor having a polyphase field winding and a commutated armature wind-

ing, a polyphase arrangement of movable brushes and a polyphase arrangement of stationary brushes bearing on the commutator of said armature winding, a polyphase series transformer connected between said stationary brushes and said movable brushes so that varying degrees of series excitation can be produced in the armature winding by moving said movable brushes, and a polyphase shunt transformer adapted to be connected to certain of said brushes. 25

In witness whereof, I have hereunto set my hand.

WILLEM C. KORTHALS-ALTES.
